United States Patent

Des. 238,143
Patented Dec. 23, 1975

238,143

BOTTLE

J. Myron Bay, 990 Lake Shore Drive,
Chicago, Ill. 60611

Filed Oct. 15, 1973, Ser. No. 406,604

Term of patent 14 years

Int. Cl. D9—01

U.S. Cl. D9—48

FIG. 3

FIG. 1

FIG. 4

FIG. 2

FIG. 1 is an elevational view of a bottle embodying my new design;

FIG. 2 is an elevational view looking from the left of FIG. 1;

FIG. 3 is an elevational view looking from the right of FIG. 1; and

FIG. 4 is a top plan view thereof.

The heavy stippling at the top indicates coloring in contrast to that of the lighter stippling.

I claim:

The ornamental design for a bottle, substantially as shown and described.
